UNITED STATES PATENT OFFICE.

JAMES S. BURGESS, OF CHARLESTON, ILLINOIS.

GATE.

SPECIFICATION forming part of Letters Patent No. 431,553, dated July 8, 1890.

Application filed February 20, 1890. Serial No. 341,171. (No model.)

To all whom it may concern:

Be it known that I, JAMES S. BURGESS, a citizen of the United States, residing at Charleston, in the county of Coles and State of Illinois, have invented certain new and useful Improvements in Gates; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to road-gates; and it has for its object to provide a gate of this character which will be simple in construction, cheap as to cost, easy to manipulate, and positive in operation.

20 My invention consists of certain novel features of construction and peculiar combinations of parts, all of which will be hereinafter fully described in the annexed specification, and particularly pointed out in the claims.

25 In the drawings, Figure 1 is a perspective view showing the gate closed. Fig. 2 is a top plan view of the same, showing the gate open in dotted lines; and Fig. 3 is a detail view, hereinafter referred to.

30 In the accompanying drawings, A indicates the gate, which is hinged at one end to a post B in such a manner as to swing across the roadway at right angles thereto, its forward end being adapted when closed to engage the 35 abutment or latch-post C.

This gate may be of any desired construction; but I preferably make it in the manner shown in the drawings.

30 D D' denote posts secured at the side of the roadway in line with post B. In the upper end of these four posts I journal a rock-shaft E. By reference to the drawings it will be seen that the ends of the shaft E are provided with depending arms e e', which are ar-

45 ranged to be in convenient reach of a person on horseback or in a vehicle. The rock-shaft E and its arms e e' may be formed of any material; but for cheapness, strength, and durability I construct the same of sections of gas- 50 pipe, joined as shown in the drawings.

F denotes an arm, which projects downward from the rock-shaft, being connected by

a T-coupling, as shown. This arm when the shaft F is rocked to close the gate extends forward of the vertical axis of the shaft E 55 and rearward thereof when the gate is swung open.

To the lower end of the arm F is connected the upper end of a rod G, the lower end of which is linked, as at g, to a diagonally-disposed articulated or toggle bar H, the lower end of which is hinged, as at h, to the lower edge of the post D', while the upper end is hinged to the diagonal brace-bar a of the gate.

The particular construction of the bar H is most clearly illustrated in Fig. 3 of the drawings, from which it will be observed that I construct the same of the sections H' H², hinged together at their meeting ends, as 70 shown at h², and form the section H' with an extension h', which overlaps the forward end of the section H² and is provided on such extended end with an eye h³ for convenient connection with the link g, as shown.

The operation of my improved gate is as follows: When the gate is in a closed position and the person desiring to pass through the gate comes in the direction indicated by the arrow in Fig. 1, by taking hold of the arm e and turning it in the direction indicated by the arrow marked 1 he will rock the shaft, raise the toggle-arm H, and start the gate to swing in the direction shown by the arrow in Fig. 2. As soon as the arm F has passed 85 its vertical position the momentum of the gate will cause the toggle-arm sections H' H² to double up, the gate assuming a position parallel with the roadway, abutting against the post D', as shown in dotted lines, Fig. 2. 90 Now, when the rider has passed through the gate and pulls the arm e' in the direction shown by arrow 3 the rock-shaft will raise the toggle-bar, which will push the gate to a closed position, serving to hold the same secure without the necessity of a latch.

From the foregoing description, taken in connection with the accompanying drawings, the advantages of my gate will readily appear.

Having thus described my invention, what I claim, and desire to secure by Letters Patent, is—

1. An improved road-gate, consisting of a gate hinged to swing across the road, a rock-

shaft journaled parallel to the roadway at the rear of the hinged portion of the gate, a toggle-bar connected at one end to the gate and at the other end to a support at a plane below its upper connection, and a flexible connection between said toggle-bar and the rock-shaft, substantially as and for the purpose described.

2. The combination, with the gate A, hung at one end, as shown, and a toggle-bar arranged diagonally downward, its upper end hinged to the gate, and its lower end hinged to a support, as D', of a rock-shaft arranged to the rear of the gate at right angles thereto, said rock-shaft having a depending arm, a flexible connection between said arm and the toggle-bar, and means for rocking the shaft, all arranged substantially as and for the purposes described.
3. The combination, with the gate A and its abutting post C, and the toggle-bar connection H, consisting of the arms H' H², hinged to-

gether, as at h³, the arm H', hinged to the gate about centrally thereof, and the arm H², hinged at its lower end to a support, as at D, said arm H' provided with a projection N', of a rock-shaft journaled to the rear of and at right angles to the gate, said shaft extended to each side of said gate and provided with depending arms e e' at its ends, a fixed arm E, depending from the rock-shaft and extending normally forward of the vertical axis of the shaft, and a flexible connection, as G, between the arm E and the projection H², all arranged substantially as and for the purposes described. 30 35

In testimony whereof I affix my signature in presence of two witnesses.

JAMES S. BURGESS.
